FOUNTAIN PAINTBRUSH

Filed Oct. 1, 1927.

INVENTOR:
Lillian G. Walker
by Edward Smith & Tenant.
Atty

UNITED STATES PATENT OFFICE

LILLIAN G. WALKER, OF NEWTON, MASSACHUSETTS

FOUNTAIN PAINTBRUSH

Application filed October 1, 1927. Serial No. 223,339.

This invention relates to fountain paint brushes and has for its main object to provide a brush of the type disclosed in which paint will be fed continuously to the periphery of the bristles and be caused to flow down the exterior layers of the bristles to a greater extent than to the interior of the brush, a condition which greatly increases the efficiency of the brush.

Another object of this invention is to provide a fountain brush capable of withstanding hard usage. The core of the brush is made solid and is bound by metal bands, there being no interior paint conduits to thus weaken the structure.

A further object of the invention is to provide a structure wherein a solid mass of bristles may be employed which is one of the important advantages of the ordinary type of brush which is used by dipping into a pail of paint.

A further object of the invention is to provide a fountain brush which has interchangeable bristle-holding elements thereby supplying the means of renewing the bristles whenever they become worn.

A further object is to provide a fountain brush that is readily cleaned after use. By removing the bristle holding element, free access may be had to the various parts of the device which are subject to becoming clogged and rendered inoperative.

Other objects and features will more fully appear in the following description and claims and will be particularly pointed out in the drawings.

Briefly the brush consists of a hollow handle member to contain the paint into which is detachably secured a bristle holding element. This latter feature makes it possible to have brushes of various shapes and sizes from which may be chosen a brush suitable for the particular work at hand. The handle has at one end a valve and a compressible bulb at its other end with which the flow of paint to the bristles is controlled. In the drawing I have illustrated one particular embodiment of the invention.

In the drawings:

Fig. 1 is a central longitudinal sectional view of the brush.

Fig. 2 is a cross section on the line 2—2 of Fig. 1.

Fig. 3 is a view similar to Fig. 2 showing the parts in a different relative position.

Fig. 4 is a section on line 4—4 of Fig. 1.

Fig. 5 is a section on line 5—5 of Fig. 1.

Fig. 6 is a perspective view of a bristle-holding element in which the mass of bristles are rectangular in form.

Referring to the drawings, 1 represents a hollow handle having an enlarged base 2 at its lower end and a compressible bulb 3 of rubber or other suitable material. The lower end of the handle is closed by a flanged wall 4, which has a valve member 5 fitted closely thereto. The wall 4 is provided with a series of apertures 6 and the valve member 5 is provided with a series of cooperating apertures 7 which may be brought into or out of alignment by rotating the valve member 5 about its pivot 8. The lower edge of the handle 1 is provided with a bead 9 which extends into a groove in the valve member 5 to retain the valve member tightly against the wall 4. The valve member 5 is provided with an extension 10 which overlies a portion of the lower section 2 of the handle. This extension provides a ready means of rotating the valve member. The inner vertical wall of the valve member 5 is provided with screw threads 4'.

A bristle-holding element 11 is provided and has screw threads at its upper end adapted to be engaged by the threads 4' in the valve member. The bristle-holding member is of special construction. It is composed of a core of bristle-anchoring material 12 which secures one end of the bristles 13. Surrounding the core of anchoring material is a metal band composed of two concentric sections 14 and 15. The internal section 15 is formed with a plurality of paint conduits 16. It will be noted that the section 14 of the band is extended downwardly over a portion of the bristles, thus forming a peripheral chamber 17.

Figs. 2 and 3 illustrate the action of the valve member in controlling the flow of paint. In Fig. 2 the valve member is rotated so that

the apertures in the wall register with those in the valve member to allow the paint 18 to flow to the conduits 16 and thence to the bristles 13. Fig. 3 shows the apertures 6 and 7 in a position out of alignment which effectively stops the flow of paint.

To operate the device, the valve member 5 is rotated to align the apertures 6 and 7, which allows the paint to flow. The bulb 3 is then manually compressed, which forces paint through the valve openings and thence through the conduits 16 to the chamber 17, where it is directed against and forced into the external layers of the bristles and flows down the bristles in the proper manner to be applied to the surface of the object to be painted.

Obviously when the device is not in use, the valve is closed to prevent further flow of paint to the bristles. In order to restore atmospheric pressure within the handle, the bulb 3 is provided with an inwardly opening check valve 19. This valve is necessary in order to permit the bulb to return to its normal condition after it has been manipulated. To introduce paint into the handle, the bulb 3 is removed, thus providing access to the paint chamber 20.

Fig. 6 illustrates a bristle-holding member 30 having a cylindrical end adapted to be received by the handle, but having its mass of bristles rectangular in shape as distinguished from the brush of circular cross section illustrated in the main views. It will thus be seen that a brush having any desired shape may be similarly adapted to use in this device.

In using the brush in a more or less upright position, the paint will flow by gravity from the reservoir in the handle into the peripheral chamber surrounding the bristles and thence on to the exterior surface of the bristles, thus enabling the paint to be applied in a most economical and efficient manner. When the brush is held in the opposite or upside down position, air pressure applied by means of the bulb will force the paint from the reservoir into the peripheral chamber and thence on to the bristles. Thus by aid of the bulb the brush is available for use in any position.

Having thus described the invention, what is claimed as new, and desired to be secured by Letters Patent, is:

1. A fountain paint brush comprising a handle hollow to constitute a reservoir for the paint and provided with a longitudinally projecting rim, a bristle-holding member having a solid core of bristles secured therein and detachably secured to the handle within the rim, the said member having a skirt extending longitudinally part way of the bristle core having its lower edge positioned to engage the bristles to form therewith a peripheral chamber, the said member also presenting a plurality of conduits extending

from the top thereof to the peripheral chamber, whereby paint fed from the handle reservoir may flow through said conduits into the peripheral chamber and thus be fed to the exterior layer of the bristles.

2. A brush having the construction defined in claim 1, together with hand operated means including a collapsible bulb, an inwardly opening check valve adapted to co-operate with said means to create pressure or to prevent a vacuum within the reservoir thereby respectively forcing paint to the bristles or allowing it to flow by gravity thereto.

3. A fountain brush for freely flowing paint comprising a handle hollow to constitute a reservoir for the paint and provided with a longitudinally projecting rim, a bristle-holding member having a solid core of bristles secured therein and detachably secured to the handle within the rim the said member having a skirt extending longitudinally part way of the bristle core having its lower edge positioned to engage the bristles to form therewith a peripheral chamber, the said member also presenting a plurality of conduits extending from the top thereof to said peripheral chamber, whereby paint fed from the handle reservoir may flow through said conduits into the peripheral chamber and thus be fed to the exterior layer of the bristles and a check valve opening inwardly to the reservoir whereby the escape of liquid therefrom is prevented when brush is in inverted position or such position that the paint is in contact with the valve, and when the brush is in a substantially upright position air is allowed to flow therein to permit the liquid to flow by gravity to the bristles.

In testimony whereof, I have signed my name to this specification.

LILLIAN G. WALKER.
